UNITED STATES PATENT OFFICE.

HENRY J. REINHARDT, OF CHICAGO, ILLINOIS.

RAIL-JOINT.

1,011,371.

Specification of Letters Patent. Patented Dec. 12, 1911.

Application filed March 8, 1911. Serial No. 613,023.

To all whom it may concern:

Be it known that I, HENRY J. REINHARDT, a citizen of the United States, and a resident of the city of Chicago, county of Cook, and 5 State of Illinois, have invented certain new and useful Improvements in Rail-Joints, of which the following is a specification.

My invention relates to improvements in rail-joints and has for its object the 10 provision of an improved rail-joint adapted to permit the running of trains thereover without noise or vibration.

The invention consists in the combination and arrangements of parts hereinafter described and claimed.

My invention will be best understood by reference to the accompanying drawing forming a part of this specification and in which—

20 Figure 1 is a perspective view of a rail-joint embodying my invention; Fig. 2, a perspective view of one of the abutting ends of a rail section constructed in accordance with my invention, Fig. 3 is an end view of one 25 of the rail sections, Fig. 4, a vertical section taken on the line $x-x$, of Fig. 2, and Fig. 5 is a top plan view of the rail-joint.

The preferred form of construction as 30 illustrated in the drawing comprises similar rail sections 1 having their abutting ends formed without webs so that the upright portion thereof is of a uniform thickness in cross section as shown. Each of the sections 1 is formed with a projecting tongue 2 and 35 a recess 3 adapted to receive the tongue on the other section as indicated. A retaining abutment 4 is formed on the flange of each rail section adjacent the corresponding recess and serves to position, and secure from 40 lateral displacement, the tongue resting in

the corresponding recess. The tongues 2 are secured together by means of bolts 5 passed therethrough as shown, said bolts serving to secure said rails against longitudinal and lateral displacement, being reinforced in the latter function by the abutments 4. The joint thus formed constitutes a firm and rigid connection between the rail sections and will permit the running of trains thereover without noise or vibration. 45 50

While I have illustrated and described the preferred construction for carrying my invention into effect this may be capable of variations and modifications without departing from the spirit of the invention. I, 55 therefore, do not wish to be limited to the exact details set forth, but desire to avail myself of such variations and modifications as come within the scope of the appended claim. 60

Having described my invention what I claim as new and desire to secure by Letters Patent is:

A rail-joint comprising rail sections having each of their abutting ends formed 65 without webs and provided with a tongue and a recess, the tongue on one rail section being adapted to fit the recess on the other, a retaining abutment formed on the flange of each rail section adjacent the corresponding 70 recess; and bolts passed through said tongues, substantially as described.

In testimony whereof I have signed my name to this specification in the presence of two subscribing witnesses.

HENRY J. REINHARDT.
